UNITED STATES PATENT OFFICE.

HUGO E. GRIESHABER, OF GROTON, CONNECTICUT, ASSIGNOR TO ELECTRIC BOAT COMPANY, A CORPORATION OF NEW JERSEY.

EXHAUST SYSTEM FOR SUBMARINE VESSELS.

1,383,398.

Specification of Letters Patent.

Patented July 5, 1921.

Application filed August 14, 1920. Serial No. 403,578.

To all whom it may concern:

Be it known that I, HUGO E. GRIESHABER, a citizen of the United States, residing at Groton, in the county of New London, State 5 of Connecticut, have invented certain new and useful Improvements in Exhaust Systems for Submarine Vessels; and I do hereby declare the following to be a full, clear, and exact description of the invention, such as

10 will enable others skilled in the art to which it appertains to make and use the same.

This invention relates to submarine engines and more particularly to means for closing the exhaust ports of such engines 15 upon submergence and opening them upon emergence.

When cruising upon the surface, submarine vessels are commonly driven by means of an internal combustion engine located within 20 the hull of the boat and having its muffler and exhaust located within the superstructure. When submerged, driving power is drawn from electric accumulators or storage batteries charged by means of a generator 25 operated by the engine during surface running. When the ship submerges the exhaust must be instantly closed. Otherwise water would be free to enter the exhaust passages, causing irreparable damage to the 30 engine and, under certain conditions, flooding the interior of the vessel itself.

A closure mechanism which can successfully perform this function of sealing the exhaust port must meet certain exacting requirements: First, it must be operable from the interior of the boat and operable upon an instant's notice. Second, the valve or closure proper must form a water-tight seal when seated upon the end of the exhaust 35 pipe. This means that it must be provided with a yieldable seat, such as one made of rubber, or with a metal seat ground true. In either event the valve must be protected from the heat of the exhaust gases when not 40 in use, and this then, is a third requirement. It is accordingly an object of this invention to provide a closure mechanism which shall fulfill these requirements.

To this end a section of the exhaust pipe 50 is made removable and mounted to swing out of alignment with the rest of the pipe. A valve is mounted above the exhaust and is so linked up with the swinging pipe section that when the latter swings out of position 55 the valve swings downwardly into position

and closes the open end of the exhaust. When the pipe section is moved back into alignment, the valve swings away and is protected from the exhaust gases by the then uninterrupted length of the exhaust pipe. A 60 vertically reciprocating rod operated by mechanism within the hull of the boat governs the movements of the pipe section and valve described above.

In order that the invention may be more 65 clearly understood reference is had to the accompanying drawings disclosing a preferred embodiment thereof. In the vessel shown in these drawings, twin engines are employed, and accordingly two symmetrically disposed closure mechanisms are used. As both these mechanisms are, however, identical in structure and operation, only one 70 has been shown, and only one will be described. The relation of the two will be 75 apparent from the drawings themselves; in which,

Figure 1 is a vertical section through the hull of the vessel and the exhaust, showing the movable section of the exhaust pipe 80 swung out of alignment, and the closure seated upon the end of the exhaust. The mechanism within the hull of the ship through which these parts are operated is shown in elevation and partly in section; 85

Fig. 2 is a plan showing the removable section of the exhaust pipe in position, and the valve raised and in operative position;

Fig. 3 is a plan of the operating apparatus situated within the hull of the vessel; 90

Fig. 4 is a diagrammatic sketch of the link movement by means of which motion is transmitted from the prime moving apparatus to the movable pipe section and the closure proper; and 95

Fig. 5 is a section taken on line 5—5 of Fig. 1, showing the reciprocating cross head of the operating mechanism in detail.

In the drawings 1 represents the hull of the vessel which is provided with the ordinary superstructure (not shown) in which is located the exhaust mechanism comprising in general a muffler 2 and a substantially horizontal exhaust pipe or passage 3. During surface cruising this exhaust pipe 100 carries the exhaust gases to the side of the superstructure and away. Within the exhaust pipe, and just beyond the muffler, there is provided a movable intermediate section 4 integral with and supported by a 110

shaft 5 journaled for oscillating movement in bearings 6 mounted upon frame-work 7. The section 4 thus mounted may be swung out of alinement with the rest of the exhaust pipe, as shown in Fig. 1. In order that this swinging motion may be readily effected the ends of the section 4 and the corresponding ends of the exhaust pipe 3 are cut upon circular lines, and in order that a reasonably gas tight joint may be made when the exhaust pipe is continuous and functioning, both open ends of the exhaust pipe and the ends of the section are provided with offset and coöperating flanges 8 and 9, respectively.

A valve or closure proper 10 is supported upon an arm 12 fixed upon a shaft 13 which is journaled for oscillatory movement within bearings 14 mounted upon the end of the muffler casing 2. This valve is provided with an annular gasket 15 made of rubber or other suitable, yielding material, or it may be provided with a metallic surface ground true. During submergence this valve 10 is seated upon an angularly disposed annular seat 16, which encircles the otherwise open end of the exhaust pipe 3.

Movable section 4 and valve 10 move simultaneously, the one into and the other out of operative position, and vice versa. These coördinated movements are effected by means of a link movement, shown most clearly in Fig. 4. Integral with the outer end of shaft 5, upon which section 4 is mounted, is an arm 17, and integral with the outer end of shaft 13, upon which valve 10 is ultimately fixed, is a similar arm 18. Connecting these two arms 17 and 18 is a loosely mounted link 19. Thus when the valve 10 is moved downwardly in a counter-clockwise direction, section 4 swings toward the vertical in a clockwise direction.

These movements are effected through the instrumentality of an arm 20 fixed upon the inner end of shaft 13, a pitman 41 and a vertically moving rod 22, which is reciprocated by means of mechanism situated within the hull of the vessel.

This mechanism, which is shown most clearly in Figs. 1 and 3, is supported by a depending frame-work 23 made fast to the hull 1 of the vessel. It comprises an air cylinder 24 which effects a movement of a piston rod 25, to which is secured a reciprocating cross head 26 sliding in suitable ways 27. Projecting laterally from either side of this cross head are cross arms 28 and 29 at the extremities of which connecting rods 30 and 32 are pivoted by means of ball and socket joints 33 and 34, respectively. These connecting rods 30 and 32 are operatively connected with the upper arms of bell crank levers 35, which are integrally mounted upon a common shaft 37, journaled within a depending bracket 39, extending from cylin-

der 24. The lower arm of bell crank lever 35 is connected to rod 22 through a link 40. The lower arm of the bell crank lever 36 is similarly connected through a link 42 to a vertical rod analogous to rod 22. This rod and its attendant mechanism, 29, 32 and 36, operate the closure on the starboard engine (not shown).

The operation of the apparatus is as follows: The ship is cruising upon the surface, section 4 is in position and valve 10 is raised into inoperative position, as indicated by dotted lines in Fig. 1 and in full lines in Fig. 2. The necessity for submergence arises. An operator within the vessel turns a cock which admits compressed air into the right hand end, as shown, of cylinder 24. This causes a movement of piston rod 25 and cross head 26 toward the left. This movement is transmitted through connecting rod 30, bell crank lever 35, link 40, rod 22, arm 20 and the rest of the link mechanism shown in Fig. 4, to swing valve 30 downwardly into position, and section 4 vertically out of position. This movement takes place rapidly and with sufficient force to seat the valve 10 firmly upon its seat 16 and thus effectively prevent the entrance of any sea water into the exhaust pipe 3, and from this into the engine and the ship itself. Upon emerging, action of the parts is reversed, valve 10 retracted and section 4 swung back into alinement. When in this position it is clear that the sealing surface of the valve 10 is amply protected from the heat of the exhaust gases.

In the event of accident to the air compressor or cylinder 24, an emergency hand gear is provided by means of which the closure mechanism may be operated. This gear comprises a hand wheel 43 which turns a shaft 44 upon which are mounted worms 45. These worms mesh with worm wheels 46 journaled within suitable bearings 47 in the frame of the ways 27. These worm wheels 45 and the coaxial extensions thereof 48 are internally threaded and coöperate with threaded feed screws 49 passing through them. These feed screws are fixed at their inner ends within cross head 26. Thus by rotation of hand wheel 43 the cross head 26 may be made to slide in either direction, and thus operate the closure mechanism through the link movement described above.

Although one specific embodiment of the invention has been described in detail, it is to be distinctly understood that the invention in its broader aspects is not limited to these details of construction. For instance, the use of compressed air has been instanced as the motive power used in the reciprocation of cross head 26. It is clear, however, that steam might well be used, and that as a matter of fact any means such as the hand gear described might be used to

effect this sliding movement. Other changes of similar nature will readily suggest themselves to those skilled in this art.

I claim:

5 1. A submarine boat having a hull, an internal combustion engine therein, an exhaust passage for the engine leading outside the hull, a movable intermediate section in this exhaust passage designed to be moved 10 out of alinement with the rest of the passage, and a closure designed to close the end of the exhaust passage when the movable section is moved out of alinement.

15 2. A submarine boat having a hull, an internal combustion engine therein, an exhaust passage for the engine leading outside the hull, a movable intermediate section in this exhaust passage designed to be swung out of alinement with the rest of the passage, and a closure designed to be simultaneously swung over the end of the exhaust 20 passage.

25 3. A submarine boat having a hull, an internal combustion engine therein, an exhaust passage for the engine leading outside the hull, a movable intermediate section in this exhaust passage designed to be swung into and out of alinement with the rest of the passage, and a closure designed 30 to swing over the end of the exhaust passage when the movable section is swung out of alinement, and away from the exhaust passage when the movable section is swung into alinement.

35 4. The structure of claim 1 and including further, mechanism within the hull of the boat for moving the movable section and the closure.

5. The structure of claim 3 and including further, unified link mechanism controlling 40 the alternating movements of the movable section and the closure, and mechanism within the hull of the vessel operating through the link mechanism to move the section and closure.

45 6. Exhaust mechanism for submarine engines comprising the combination of an exhaust passage, a movable intermediate section therein alined with the rest of the passage during surface cruising, a closure 50 mounted near the movable section and protected from the exhaust gases by this section, the parts being so arranged that prior to submergence the movable section can be moved out of alinement and the closure 55 moved over the open end of the exhaust passage to seal it.

7. A submarine boat having a hull, an internal combustion engine therein, an exhaust passage for the engine leading outside 60 the hull, the external length thereof being substantially horizontal, a movable intermediate section in this exhaust passage pivotally supported at a point above its middle and designed to be swung about 65 said point into and out of alinement with the rest of the passage, and a closure designed to swing over the exposed end of the exhaust passage nearest the engine when the movable section is swung out of alinement, and away from the exhaust passage 70 when the movable section is swung into alinement.

In testimony whereof I affix my signature.

HUGO E. GRIESHABER.
